US00D670872S

(12) **United States Design Patent**
Woodzelle et al.

(10) **Patent No.:** **US D670,872 S**
(45) **Date of Patent:** **** Nov. 13, 2012**

(54) **LOST AND FOUND TAG**

(76) Inventors: **Patrick S. Woodzelle**, Glen Burnie, MD (US); **Daniel R. Bowman**, Glen Burnie, MD (US)

(**) Term: **14 Years**

(21) Appl. No.: **29/376,384**

(22) Filed: **Oct. 6, 2010**

(51) **LOC (9) Cl.** **30-08**

(52) **U.S. Cl.** **D30/155**

(58) **Field of Classification Search** ..... D30/155, D30/199, 151–154; D11/7, 79, 85, 97, 99, D11/107, 108, 82, 137, 105; D20/22–32, D20/10; D3/207–212, 270–271.3; D26/38; 206/37.1, 38.1; D6/302–304; D24/199; 70/456 R, 456 B, 458, 459; 24/3.6; D21/610, D21/611, 626; 119/865, 655, 51.02, 857–860, 119/719–721, 792, 795; 40/310, 665, 300–302, 40/633; D8/1, 34, 38, 18; 239/57; 362/812; D10/33; D2/976; D7/619.2

(57) **CLAIM**

The ornamental design for a lost and found tag, as shown and described.

DESCRIPTION

FIG. 1 is a front perspective view of a lost and found tag, showing our new design;

FIG. 2 is a front view thereof;

FIG. 3 is a rear view thereof;

FIG. 4 is a left side view thereof with a right side view being a mirror image;

FIG. 5 is a top view thereof; and,

FIG. 6 is a bottom view thereof.

The broken line elements are not claimed.

1 Claim, 4 Drawing Sheets
